Patented Aug. 8, 1916.

UNITED STATES PATENT OFFICE.

GEORGE W. BEHREND, OF WAUSA, NEBRASKA.

PLANTER.

1,193,501.

Specification of Letters Patent. Patented Aug. 8, 1916.

Application filed March 11, 1916. Serial No. 83,626.

To all whom it may concern:

Be it known that I, GEORGE W. BEHREND, a citizen of the United States, residing at Wausa, in the county of Knox and State of Nebraska, have invented certain new and useful Improvements in Planters, of which the following is a specification, reference being had to the accompanying drawings.

This invention relates to certain improvements in planters and has relation more particularly to a device of this kind of a check-row type, and it is an object of the invention to provide a device of this general character having novel and improved means whereby the runners may be conveniently and effectively raised or lowered and whereby the check wire may be released from its head when desired.

The invention consists in the details of construction and in the combination and arrangement of the several parts of my improved planter whereby certain important advantages are attained and the device is rendered simpler, less expensive and otherwise more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein—

Figure 1 is a view in top plan of a portion 35 of a corn planter illustrating an embodiment of my invention, certain of the parts of a corn planter being omitted for clarifying the disclosure, as the same has no relation to my present invention; Fig. 2 is a sectional view taken substantially on the line 2—2 of Fig. 1; Fig. 3 is a sectional view taken substantially on the line 3—3 of Fig. 1; Fig. 4 is a fragmentary side elevational view illustrating a means herein embodied for 40 rendering a check wire release inoperative; Fig. 5 is a sectional view taken substantially on the line 5—5 of Fig. 1; and Fig. 6 is a fragmentary view in elevation of the upper or outer end of the lever for adjusting the 45 runners downwardly.

As disclosed in the accompanying drawings, F denotes the frame of a conventional corn planter with which is operatively engaged, as at 1, the transversely disposed hopper frame H from which depends the 55 runners 2 adapted to coact with the ground

in a conventional manner. The frame H is also provided at its opposite end with the check-row wire heads 3 having their lower part open and with the under portion of 60 which coacts the swinging latch 4 for retaining the check wire within the head.

Disposed transversely of the frame F at a predetermined point rearward of the frame H is the shaft 5 rotatably supported by the 65 upstanding bearings 6 carried by the side members of the frame F. The shaft 5 is operatively engaged with the frame F as indicated at 7, whereby upon requisite rocking movement being imparted to the shaft 5 70 the runners 2 may be raised or lowered.

8 denotes a foot pedal loosely mounted upon the shaft 5 and having its hub 9 provided with the slot 10 through which passes a pin 11 carried by the shaft 5, whereby it 75 will be perceived that the pedal 8 has limited independent rocking movement relative to the shaft 5 so that the same may have an initial downward movement before the shaft 5 is caused to rotate, and as is particularly 80 illustrated in Fig. 1, the pedal 8 is automatically returned to the limit of its upward movement through the medium of the spring 12 operating in a manner which is believed to be clearly apparent to those skilled in the 85 art to which my invention appertains.

The opposite end portions of the shaft 5 are provided with the laterally directed lugs 14, each of which being provided with the straight end 15 affording a shoulder adapted to contact with the inner end of the arm 16 pivotally engaged, as at 17, with the upper end of the substantially vertically disposed rock arm 18 pivotally engaged with the frame F, and said rock arm 18 is operatively engaged through the medium of the rod 19 with the arm 20 operatively engaged with a latch 4, whereby it will be perceived that as the pedal 8 is depressed, the arm 18 will be forced rearwardly through the medium of the arm 16 a distance sufficient to adjust the latch 4 in an open position at the same time the frame H is moved in a direction to raise or elevate the runners 2. This operation is particularly desirable at the 100 time the planter has reached an end of a row so that the check wire will drop from a head 3 when it is desired to turn the planter around.

It often occurs that it is necessary to raise 110 the runners 2, especially when an obstruction is encountered along a row, without re-

leasing the check wire. For this reason I have the shaft 5 tubular and loosely disposed therethrough a supplemental shaft 21 having its opposite extremities provided 5 with the rock arms 22 terminating in the inwardly disposed extensions 23 underlying the arms 16 whereby it will be perceived that upon an upward rotative movement being imparted to the shaft 21, the extensions 10 23 will serve to elevate the arms 16 out of the path of travel of the lugs 14, and thus permit the runners 2 to be elevated under the influence of the pedal 8 without adjusting the latches 4 into open position.

15 While any means may be employed for imparting the requisite movement to the shaft 21, I prefer to employ the arrangement disclosed in the accompanying drawings, wherein one end of the shaft 21 is 20 provided with a second rock arm 24 operatively engaged through the medium of the rod 25 with the pedal 26 suitably mounted for rocking movement at one side of the frame F and at a point inwardly of the 25 shaft 5.

Fixed to the shaft 5 is a foot lever 27 having its upper extremity angularly disposed, as at 28, and arranged transversely of the frame F and in a direction away 30 from the pedal 8, and said lever 27 intermediate its length is provided with a sliding latch 29 adapted to coact with the substantially segmental rack 30 carried by a stationary part 31 of the planter, preferably 35 one of the braces for the seat structure (not shown) whereby it will be perceived that the shaft 5 is normally held against rotative movement. The pedal 8 is provided with the angular bracket 32 underlying the 40 lower end of the latch 29, whereby it will be perceived that the initial independent movement of the pedal 8 when depressed will cause the bracket 32 to raise the latch 29 out of engagement with the rack 30, and in order 45 that the runners 2 may be maintained in an elevated position, I provide the part 31 with the forwardly disposed arm 33 provided in its under surface with the notch or recess 34 adapted to receive the angular extension 50 35 of the latch member 36 carried by the lever 27.

As herein embodied, the extension 35 is disposed through a longitudinally disposed slot 37 formed in the lever 27 and the upper extremity of the latch 36 is loosely disposed through the upper angular portion 28 of the lever 27 and has operatively engaged therewith the flat spring 38 having one end anchored, as at 39, to the angular extension 60 28 of the lever 27, said spring 38 serving to normally maintain the latch 36 at the limit of its upward movement.

When it is desired to lower the runners 2, a foot of the operator is placed upon the 65 angular extremity 28 of the lever 27 and

caused to depress the spring 38 and latch 26, whereby the extension 35 is disengaged from the notch 34 of the arm 33, whereby the lever 27 is free to be moved forwardly, and as is believed to be clearly apparent, the 70 latch 29 will freely ride over the teeth of the rack 30 and serve to lock the lever 27 against return movement after the same has been moved forwardly to a desired extent.

From the foregoing description, it is 75 thought to be obvious that a planter constructed in accordance with my invention is of an extremely simple and comparatively inexpensive nature and is particularly well adapted for use by reason of the convenience 80 and facility with which it may be assembled, and it will also be obvious that my invention is susceptible of some change and modification without material departure from the principles and spirit thereof and for this 85 reason I do not wish to be understood as limiting myself to the precise arrangement and formation of the several parts herein shown in carrying out my invention in practice. 90

I claim:

1. In combination with a planter including a frame, a hopper frame supported for rocking movement by the first named frame, and runners depending from the hopper 95 frame, a transverse shaft carried by the first named frame inwardly of the hopper frame and operatively engaged with the hopper frame, a pedal mounted upon the shaft and having a limited movement independently 100 of the shaft, a lever fixed to the shaft and angularly related to the pedal, a rack carried by the frame, a latch carried by the lever coacting with the rack, and a member carried by the pedal and contacting with the latch for disengaging the latch from the 105 rack during the independent movement of the pedal.

2. In combination with a planter including a frame, a hopper frame supported for 110 rocking movement by the first named frame, and runners depending from the hopper frame, a transverse shaft carried by the first named frame inwardly of the hopper frame and operatively engaged with the hopper 115 frame, a pedal mounted upon the shaft and having a limited movement independently of the shaft, a lever fixed to the shaft and angularly related to the pedal, a rack carried by the frame, a latch carried by the lever coacting with the rack, a member carried by the pedal and contacting with the latch for disengaging the latch from the 120 rack during the independent movement of the pedal, and a second locking means coacting with the lever for holding the shaft against return movement upon predetermined depression of the pedal. 125

3. In combination with a planter including a frame, a hopper frame supported for 130

rocking movement by the first named frame, and runners depending from the hopper frame, a transverse shaft carried by the first named frame inwardly of the hopper frame 5 and operatively engaged with the hopper frame, a pedal mounted upon the shaft and having a limited movement independently of the shaft, a lever fixed to the shaft and angularly related to the pedal, a rack carried by the frame, latch carried by the lever 10 coacting with the latch for disengaging the latch from the rack during the independent movement of the pedal, a second locking means coacting with the lever for holding the shaft against return movement upon predetermined depression of the pedal, and means carried by the lever for releasing said second locking means. 15

4. In a planter, the combination with a frame, a hopper frame pivotally carried 20

thereby, runners depending from the hopper frame, a check wire head carried by the hopper frame and having its lower end open, and a latch normally underlying the open portion of the head, a shaft rotatably supported by the first named frame and operatively engaged with the hopper frame, means for rocking the shaft, means operated by the shaft when rocked in one direction for releasing the latch of the check wire 25 head, and independent means for rendering said last named means inoperative upon rocking of the shaft. 30

In testimony whereof I hereunto affix my signature in the presence of two witnesses. 35

GEORGE W. BEHREND.
